MASONRY DRILL BIT

Charles L. Pedersen, Englewood, Colo., assignor of one-half interest to Lee Holmes and David P. Chenault, both of Littleton, Colo.

Filed Oct. 6, 1965, Ser. No. 87,334

Term of patent 14 years

(Cl. D54—4)

FIG. 2.

FIG. 5.

FIG. 1.

FIG. 4.

FIG. 3.

FIG. 6.

FIGURE 1 is a front elevational view of the masonry drill bit, showing my new design;

FIGURE 2 is a top view thereof;

FIGURE 3 is a bottom view thereof;

FIGURE 4 is a side elevational view thereof;

FIGURE 5 is a sectional view taken along line 5—5 of FIGURE 1; and

FIGURE 6 is a sectional view taken along line 6—6 of FIGURE 3.

I claim:

The ornamental design for a masonry drill bit, as shown.
